His Attorney.

UNITED STATES PATENT OFFICE

GLENN B. WARREN, OF SCHENECTADY, NEW YORK, ASSIGNOR TO GENERAL ELECTRIC COMPANY, A CORPORATION OF NEW YORK

TURBO-GENERATOR INSTALLATION

Application filed May 23, 1929. Serial No. 365,415.

The demand by central stations and other users of power generating apparatus is on the one hand for very large units while on the other hand the available floor space in the 5 stations is greatly restricted and, in the majority of cases, cannot be enlarged for reasons which will be appreciated. This has led to placing the turbines one above the other and also the generators one above the other. 10 This arrangement, while it has many advantageous features, is open to the serious objection that to open the low pressure turbine for inspection or repair involves disassembling and removing the high pressure unit as well, 15 a proceeding which costs a large sum of money in itself and greatly increases the period of time that the apparatus as a whole out of service. This latter has a direct bearing on operating costs and may, and usually does, 20 seriously handicap the station in supplying current to its customers.

In order that an idea may be had of the great weights involved in these turbine installations, reference may be made as an example to a two unit machine of 50,000 kilowatts output, of which I have knowledge. In this case the high pressure unit weighs approximately 90,000 pounds and the cover of the casing, diaphragms and upper half of 25 the exhaust hood of the low pressure unit weigh approximately 80,000 pounds.

I have invented an arrangement of turbines and generators which has all of the advantages of saving floor space and at the 30 same time permits the turbines and generators to be opened separately, and this without interference from the other parts of the assembly. Briefly stated, my invention comprises dividing the turbine into two principal 35 parts or units, and to attain the greatest benefits of the invention the high pressure unit is made much smaller than the low pressure unit, say of the order of thirty percent for the former and seventy percent for the latter. 40 The low pressure turbine and its generator are, due to their great weight and size, mounted on the foundation of the station and in axial alignment. Upon the generator are mounted the smaller high pressure turbine 45 and its smaller generator, and so arranged 50

that no portion overhangs the low pressure turbine in a manner to prevent it from being opened. For this purpose the casing of the generator driven by the low pressure turbine is so shaped and constructed as to afford a 55 firm foundation for the parts supported thereby.

For a consideration of what I believe to be novel and my invention, attention is directed to the accompanying description and the 60 claims appended thereto.

In the drawing, Fig. 1 is a view in side elevation of a cross compound turbine generator unit which is illustrative of my invention, and Fig. 2 is an end view of the same. 65

As an illustration, but not as a limitation of my invention, I have elected to illustrate it in connection with an installation of 50,000 kilowatts capacity.

3 indicates a support which may be a steel 70 or concrete foundation or a bed plate which is supported thereby. Upon the support or foundation is mounted a low pressure turbine 4 of large capacity having an exhaust housing 5 adapted to be connected to a condenser 75 6 of which only the upper part is shown. The casing of the turbine is split in a horizontal plane as is usual and is so arranged that it can be lifted to expose the wheels and other parts without interference from any 80 other part of the assembly. The front end of the turbine casing is supported by brackets 7, one on each side, which are arranged to take care of expansion strains due to heat. These brackets are supported by a suitable support 85 member carried by the foundation or by a separate pillar as desired. Exhaust fluid, such as steam, is admitted to the turbine by the inlet 9 from the exhaust opening or openings 10 of the high pressure unit. In some 90 cases it is desirable to reheat or to superheat the fluid in its passage from one unit to the other, and a means for this purpose is indicated at 11. The piping has been shown by a broken-and-dotted line 12 for simplicity of 95 illustration. At the left hand end of the turbine in addition to the shaft bearing is a speed governor indicated by the reference character 8^a, and below it is an oil tank 8^b from which oil is supplied by a pump to the bearings, 100

The massive electric generator which is driven by the low pressure unit is indicated at 13. As the internal construction is unimportant to the present invention it has not been illustrated. It is sufficient to say that the casing forms a unitary structure and that the rotor may be removed by an endwise movement according to standard practice. The shafts of the two machines are in axial alignment and are coupled by any suitable or well-known means. On the outer end of the generator shaft is a bearing 13^a and a smaller generator 14^a which may supply current for energizing the field winding of both generators, for driving auxiliaries or for any other purpose.

The casing of the generator 13 may be made somewhat heavier than is necessary for purely electrical reasons, in order to support the load placed on top of it, and is finished differently on the top, being flat. Supported wholly by the generator casing is a high pressure turbine 14 and an electric generator 15, the shaft axes of the turbine units and generators being in the same vertical plane. As shown, they are mounted on a bed plate 16 which in turn is fastened to the casing of the large generator 13. The high pressure turbine and its generator are so supported that there is nothing to interfere with the raising of the casing or the exhaust housing of the low pressure turbine to expose the internal parts. In other words, the high pressure turbine unit is displaced in an axial direction with respect to the low pressure turbine unit. The casing of the high pressure unit is split in the horizontal axial plane and there is nothing to interfere with raising the upper part to expose the internal parts. The high pressure unit is mounted on the end of the generator adjacent the low pressure unit so that the length of the conduit connecting the two in series as regards the flow of motive fluid may be reduced to a minimum. One outstanding advantage of the arrangement is that the high pressure unit does not have to be lifted or opened or its alignment affected when work is being done on the low pressure unit. As illustrated, the turbine and its generator have a capacity of about thirty percent of the total, the low pressure turbine and its generator furnishing the remainder. The shafts of the turbine and generator are in the same axial plane and they may be connected by any suitable or usual means. The shafts of both the upper and lower units are in the same vertical plane, and as far as possible the metal used in each construction is symmetrically disposed about its shaft so as to reduce the distortion effects due to heating. Steam or other elastic fluid under high pressure is admitted to the high pressure unit by the conduit 17 subject to the control of a combined emergency and throttle valve 18 of any suit-

able construction. For convenience the operating means for the valve is located at the level of the main foundation. In addition, any suitable speed governor, such as indicated at 19, and valves may be employed to regulate the supply of motive fluid in accordance with changes in load. The large and small main generators may be electrically connected in parallel so that only one speed governor and regulating means is required for both units, or they may be separately controlled or controlled by the governor 8^a.

By dividing the total capacity of the apparatus on about the basis mentioned the lower generator will be large enough to support both the high pressure unit and its generator without requiring any additional metal except possibly a small amount to give to the lower casing the proper shape.

The arrangement has the advantage that it eliminates the necessity of a separate foundation in the power house for one turbine, i. e. the high pressure unit. Another and outstanding advantage is that the casing of both turbines can be opened, one without disturbing the other, and from overhead. The generators can also be opened or inspected without disturbing the turbines. It also permits, due to their location one over the other, of the use of a single cooling system for both generators, passing the air or other cooling medium from one directly to the other in the region of their meeting surfaces. For example, cool air may be supplied to the lower generator by the conduits 20 and 21 and after passing through both generators is delivered to the conduit 22 which may be taken as a part of a cooler or as a conduit leading thereto.

Eliminating one foundation reduces the cost of the installation and saves valuable floor space which would otherwise be required, and furthermore the large generator 13 affords a substantially better foundation for the other generator and its turbine than is usually provided or in many cases is possible to provide.

Dividing the turbine into two units of the capacity stated makes a very advantageous division of the load for reheating or superheating of the motive fluid between the two units since the volume of fluid to be handled will require only conduits of reasonable size and cost.

What I claim as new and desire to secure by Letters Patent of the United States, is:

1. A turbine generator installation comprising a low pressure turbine and a generator driven thereby, a foundation therefor, a high pressure turbine and a generator driven thereby which are supported wholly by the firstnamed generator and are both axially displaced from the low pressure turbine unit by such an amount that the casing of the latter may be opened without disturbing the

high pressure unit, and conduit means for supplying motive fluid to the turbine units.

2. A turbine generator installation comprising high and low pressure turbine units, the former being of lower capacity than the latter, generators driven by the turbine units each of which is in axial alignment with its driving unit, the high pressure unit and its generator being wholly supported by the generator of the low pressure unit with the axes thereof occupying the same vertical plane as the axis of said generator, a foundation for the low pressure unit and its generator, and conduits for supplying motive fluid in series 10 to the two turbine units.

15 3. A turbine generator installation comprising a foundation, a low pressure turbine, a generator driven thereby, said turbine and generator being mounted on the foundation 20 in axial alignment, a high pressure turbine unit, a generator driven thereby which parts are also in axial alignment, said unit and its generator being wholly supported on top of the first named generator and being axially 25 displaced from the low pressure turbine unit to permit of the latter being opened to expose its internal parts without interference, the high pressure unit being located at the end of the generator adjacent the low pressure unit 30 so as to reduce the length of the connecting conduit, and a conduit for conveying the exhaust of the high pressure unit to the low pressure unit.

In witness whereof, I have hereto set my hand this 21st day of May, 1929.

GLENN B. WARREN.
